REFRIGERATING APPARATUS

Edward B. Newill, Dayton, Ohio, assignor to General Motors Corporation, Dayton, Ohio, a corporation of Delaware

Application April 18, 1939, Serial No. 268,544

5 Claims. (Cl. 62—125)

My invention relates to refrigerating apparatuses and more particularly to refrigerating apparatuses utilizing a plurality of closed refrigerant circuits.

5 In the production of refrigerating apparatuses and particularly household refrigerator cabinets, it has been the practice to mount an evaporator, adapted to receive and store frozen food products and to receive trays of water to be frozen, 10 within the food storage compartment of the cabinet. The low temperature of outer walls of the evaporator has been employed to cool and cause circulation of air within the main storage compartment of the cabinet for refrigerating other 15 products not requiring as low storage temperature as frozen food products. It is known that this method of refrigerating the main food storage compartment of a refrigerator cabinet necessitates operation of the evaporator at such low 20 temperature that its walls cause moisture to be condensed out of the circulated air and deposited on the evaporator walls. The withdrawal of moisture from the air causes dehydration of certain foods stored in the storage compartment. 25 While I have found that this low temperature of the evaporator air cooling walls and its resultant withdrawal of moisture from the air and from certain foods has not been objectionable to many users of refrigerating apparatuses, other users have strenuously objected to this method of refrigeration because most of the foods these other users store in the refrigerator have been of a moisture laden or bearing variety. Therefore, my invention is particularly 30 directed to a method of refrigerating a household refrigerator cabinet that can be selectively employed in conjunction with a conventional refrigerating system to meet the desirability or demands of individual users to thus render a 35 conventional refrigerating apparatus universal in utility.

An object of my invention is to provide an improved refrigerating apparatus that can be modified at will to produce different refrigerating effects within a compartment to be cooled as desired by individual users.

Another object of my invention is to provide the evaporator of a primary refrigerating system or circuit located within a household refrigerator cabinet with a member constructed and arranged to form in conjunction with the evaporator a secondary volatile refrigerant circuit or system to thereby permit the evaporator of the primary refrigerating system to be maintained 50 at a very low temperature for freezing purposes

and to utilize a higher temperature of the secondary refrigerant circuit or system for cooling other foods in the refrigerator at a temperature above freezing.

A further object of my invention is to provide a closed secondary refrigerating system or circuit of such construction that it can be readily attached to or removed from an evaporator of a primary refrigerating system within a household refrigerator to modify the effect produced by the refrigerating apparatus within the food storage compartment thereof.

A still further object of my invention is to construct a member forming a closed secondary volatile refrigerant circuit for use in conjunction with the evaporator of a primary refrigerating system located in a food storage compartment in such a manner that it has an upper part adapted to removably engage the evaporator and form the refrigerant condensing portion of the secondary circuit and with other parts thereof spaced from the evaporator and forming a shield for isolating the evaporator from the air within the compartment as well as a refrigerant evaporator portion for the secondary refrigerant circuit.

In carrying out the foregoing objects, it is a further and more specific object of my invention to provide a member adapted to form a closed secondary refrigerating system or circuit for association with and support by an evaporator of a primary refrigerating system, located in a food storage compartment of a refrigerator cabinet, and to construct the member so that it can be readily removed from the evaporator without disturbing the primary refrigerating system and so as not to interfere with the unitary removability of the primary refrigerating system from a cabinet.

Further objects and advantages of the present invention will be apparent from the following description, reference being had to the accompanying drawings wherein a preferred form of the invention is clearly shown.

In the drawings:

Fig. 1 is a vertical sectional view through a refrigerating apparatus of the household type having my invention embodied therein; and

Fig. 2 is a transverse sectional view through the refrigerating apparatus shown in Fig. 1 and is taken on the line 2—2 thereof.

Referring to the drawings, for illustrating my invention, I have shown in Fig. 1 thereof a refrigerating apparatus comprising a household refrigerator cabinet 10 including a plurality of

metal panels or shells 11 and an inner metal liner 12. The liner 12 forms a food storage compartment 14 within cabinet 10, and in order to insulate compartment 14 I place suitable packaged insulation 15 between the liner and the cabinet outer metal panels or walls 11. Walls 11 of cabinet 10 extend downwardly beyond the compartment 14 and provide a machine compartment 16 provided with mounting portions 17. A suitable insulated door 18 normally closes an access opening 19 leading to the interior of compartment 14. The back upright wall of liner 12 is provided with an opening flanged as at 20 about its edges and which opening is normally covered by a removable plate 21. The back wall 11 of cabinet 10 is also provided with an opening which is in alignment and registers with the opening in the back wall of liner 12. This opening in the cabinet back wall 11 is normally closed by a removable plate 22. I place a quantity of loose insulating material 23 between the plates 21 and 22 to prevent leakage of heat through this portion of the cabinet insulated back wall.

A closed circuit or refrigerating system, containing any suitable or desirable refrigerant, is removably associated with the refrigerator cabinet 10 and comprises a refrigerant translating device or circulating unit including motor-compressor 26 and a condenser 27 located within the machine compartment 16 and secured, by suitable brackets or the like, to the mounting portions 17 therein. The refrigerating system also comprises a refrigerant evaporating element 31 mounted within the upper part of food storage compartment 14 by a plurality of studs or bolts 32 supported by the top wall of compartment 14. A conduit 33 connects the discharge side of compressor 26 with the condenser 27 and a conduit 34 extends from the condenser 27 to the evaporator 31. A refrigerant expansion device or restrictor 35 is interposed in the conduit 34 for controlling the flow of liquid refrigerant, condensed and liquefied in condenser 27, to the evaporator. Gaseous refrigerant or refrigerant evaporated within the evaporator 31 is withdrawn therefrom by the compressor 26 through a return conduit 37 connecting the evaporator with the gaseous intake side of the compressor 26. In order to control the operation of motor-compressor 26 I place a thermostat bulb 41 at any suitable or desirable location within the food storage compartment 14. Bulb 41 has a pipe connection 42 with an expansible and contractible element or bellows (not shown) located within a control switch 43. The bulb 41, pipe 42 and the bellows of switch 43 form a closed fluid thermostatic system for actuating the electrical contacts of switch 43 in response to the temperature within compartment 14. Thus, the operation of motor-compressor 26 is controlled in response to the temperature desired to be maintained in the food compartment 14 as is conventional in such apparatus. It is to be noted that the conduits 34 and 37 and pipe 42 pass through the closure plates 21 and 22 at the back of cabinet 10 and that these conduits and pipe are sealed to the plate 21 by a single large, preferably split, grommet 45, while the conduits 34 and 37 and pipe 42 are sealed to plate 22 by individual smaller grommets 46.

The evaporator 31 of the refrigerating system may be of any suitable or desirable construction but is preferably of the sheet metal type comprising an inner metal sheet 51 and an outer metal sheet 52 welded or otherwise suitably se-

cured to sheet 51 and provided with a plurality of corrugations to form a plurality of refrigerant expansion or evaporating passages 53 between the sheets. Outer metal sheet 52 of evaporator 31 is also provided with horizontally extending corrugations forming a pair of upper gaseous refrigerant headers 55 and a lower liquid refrigerant distributing header 56. The headers 55 and 56 are in open communication with the refrigerant evaporating passages 53. Upper headers 55 are connected together and to the gaseous refrigerant return conduit 37 by a cross pipe 57 (see Fig. 2). The evaporator 31 is formed into a box-like structure and surrounds or encloses a sharp freezing chamber or compartment divided into a plurality of smaller freezing compartments by shelves 58 adapted to receive and support trays of water to be frozen or for receiving and storing frozen comestibles. The rear of the freezing chamber or compartment formed by the box-like evaporator 31 is closed by a metal wall 59 while a door 61, pivotally mounted upon the front of evaporator 31, closes the front of the freezing compartment and provides access thereto.

In order to remove the closed refrigerating system from cabinet 10, plate 22 is removed from the back wall 11 of the cabinet and plate 21 is detached from the back wall of liner 12. The plate 21 is then elevated until its hook-like peripheries clear the curved peripheral flange 20 on liner 12. The plate 21 can then be moved away from liner 12, and the split grommet 45 separated to permit removal of the conduits 34 and 37 and pipe 42 therefrom. Thermostat bulb 41 and its connecting pipe 42 are then pulled through the loose insulating material 23 and through the opening in plate 22 normally closed by grommet 46. Bulb 41 and pipe 42 are then moved away from plate 22 so as to be out of the path of movement of the plate 22 and evaporator 31 from the cabinet. The evaporator supporting studs 32 are detached from the evaporator and the means for securing the motor-compressor 26 upon its mounting 17 are removed. The closed refrigerating system can now be unitarily moved horizontally of the cabinet 10 to remove same therefrom. Evaporator 31, after removal of the insulating material 23, will freely pass through the opening in the cabinet back wall which is normally closed by the insulation 23 and plates 21 and 22.

The refrigerating apparatus thus far described may be said to be conventional, and operation of the refrigerating system will cause the evaporator 31 to produce a refrigerating effect within the food storage compartment 14 of cabinet 10 to cool and preserve food products stored therein and to freeze liquids contained in trays and located on the shelves 58 of the evaporator. This type of apparatus and the refrigerating effect produced thereby is generally satisfactory for most users of household refrigerator cabinets, but some users store a large quantity of moisture laden or bearing food products in the food storage compartment 14 and desire to refrigerate these food products at a temperature that will permit them to retain their moisture content. Since it is the aim of my invention to render the refrigerating apparatus disclosed universal in utility, I provide means that can be furnished with the apparatus at low cost to modify the refrigerating effect of the apparatus at will in order to meet the uses thereof such, for example, as when the apparatus is employed to refrigerate a quantity of moisture laden comestibles in the

food storage compartment. It is to be understood that while I desire to modify the refrigerating effect produced in the food storage compartment 14 of cabinet 10, it is also essential that the temperature within compartment 14 be maintained between predetermined limits irrespective of whether or not the refrigerating effect therein is altered or modified. Therefore, in order to accomplish the aim of my invention, I provide a double-walled metal member or structure 71 that can be readily placed into intimate thermal contact with and easily removed from the evaporator 31.

The structure or member 71 comprises an inner metal sheet 72 and an outer metal sheet 73 welded or otherwise suitably secured together about their peripheries and bent into a substantially C-shaped box-like structure. The sheets 72 and 73 are spaced apart intermediate their peripheries to provide a refrigerant chamber 74 therebetween. A volatile liquid refrigerant such as a halogen derivative of an aliphatic hydrocarbon, and for instance difluorodichloromethane, is sealed within chamber 74 which thus renders the member or structure 71 a closed secondary volatile refrigerant circuit or system associated with the evaporator 31 of the primary refrigerating system. The end portions of the inner metal sheet 72 of the C-shaped box-like structure 71 are corrugated as at 76 (see Fig. 1) to provide the member or structure 71 with inner upper surfaces shaped to correspond to the corrugations and the flat portions in the top wall of evaporator 31 of the primary refrigerating system.

Normally, the refrigerating apparatus disclosed can be operated as a conventional refrigerating system, but if too much drying of the circulating air or dehydration of foods stored within compartment 14 of cabinet 10 occurs and becomes objectionable to certain users, these users of the apparatus may place the member or structure 71 on the evaporator 31 of the primary refrigerating system. The structure 71 is generally somewhat larger than evaporator 31 and upon opening the food storage compartment door 18, it may be brought into vertical alignment with the evaporator 31 at the compartment access opening 19, and moved horizontally thereover so that the inner corrugated surface 76 of the end portions thereof are in a position to engage the top walls of evaporator 31. The structure 71 may then be lowered into position upon the evaporator 31 and supported thereby. The double-walled structure 71 substantially surrounds the evaporator 31 and has its top portions engaging the top walls of evaporator 31 and its bottom and side walls or portions spaced from the bottom and side walls of evaporator 31. Corrugations 76 in member or structure 71 fit snugly over and in intimate thermal contact with the corrugations forming the refrigerant passages 53 in evaporator 31. Thus, these portions of structure 71 contacting evaporator 31 form a refrigerant condensing portion of the secondary refrigerant circuit or system while the walls of structure 71 spaced from the evaporator 31 provide refrigerant evaporating portions for the secondary refrigerant circuit. A resilient molded rubber gasket or the like member 78, of a general U-shape in order to conform to the space between the evaporator 31 and the secondary refrigerant structure 71, closes the space between the evaporator 31 and structure 71 at the ends thereof. By referring to Fig. 1 of the drawings, wherein the cross sectional contour of gasket 78 is shown, it will be noted that gasket or closure element 78 includes a pair of flanges 79 which fit over and which may be secured in any suitable manner to the front and rear edges of structure 71 and also includes another flange 81 which is adapted to removably engage the walls of evaporator 31. Gasket 78 seals the space between the walls of evaporator 31 and walls of structure 71 and this dead air space acts to insulate refrigerant evaporating portions of the secondary refrigerant structure 71 from portions of the primary evaporator 31. The structure 71 extending around evaporator 31 substantially isolates evaporator 31 from air within the food storage compartment 14.

The operation of the apparatus with the use of the structure 71 located over and carried by the evaporator 31 comprises maintaining the evaporator 31 between predetermined temperature limits, preferably below 32° F. in order to freeze or congeal liquid contained in trays or receptacles placed in the freezing compartment formed by walls of the evaporator 31. Since the structure 71 forms a secondary volatile refrigerating system and since the major part thereof is spaced from the primary refrigerant evaporator 31, the structure 71 functions at a considerably higher temperature than evaporator 31 for producing refrigeration in the main food storage compartment 14 of cabinet 10. For example, refrigerant may be evaporated within structure 71 at any suitable or desirable temperature between 32° and 45° F. Thus, refrigerant evaporating in chamber 74 of structure 71 maintains this structure at a sufficient high temperature to prevent the withdrawal of moisture from the air within compartment 14 and thereby eliminates dehydration of foods stored in the storage compartment 14. In operation, refrigerant within the secondary refrigerating system or structure 71 evaporates between the double bottom and side walls thereof and, in so evaporating or vaporizing, removes heat from the food storage compartment 14. The evaporated or vaporized refrigerant of the secondary refrigerating system or circuit flows upwardly within structure 71 and is cooled and condensed or liquefied in the upper part thereof, in contact with evaporator 31, and again flows back into the bottom and side walls of the structure 71. Therefore, structure 71 withdraws heat from compartment 14 to cool the compartment and transfers this heat to the evaporator 31 from where it is removed by the primary refrigerating system associated with the refrigerator cabinet 10.

As before stated, the use of the secondary volatile refrigerating system or structure 71 is optional or selective, and the structure 71 can be readily removed from the evaporator 31 if desired without altering or interfering with the continued operation of the primary refrigerating system. To remove the secondary refrigerating system or circuit from the evaporator 31 of the primary refrigerating system, structure 71 is elevated so that the corrugations 76 in its upper portions will clear the corrugations of passages 53 in the top walls of evaporator 31. Structure 71 can then be moved horizontally outwardly of the food compartment 14 through the compartment access opening 19 of cabinet 10. It is to be understood that the raising of structure 71 relative to evaporator 31 is permitted by the resiliency of gaskets or closing elements 78 which are temporarily deformed. If the gaskets 78 are secured

to structure 71 as hereinbefore stated, they will be removed from evaporator 31 along with the removal of structure 71 therefrom. On the other hand, the gaskets 78 may, if desired, be separate 5 from structure 71 and placed in position after the structure 71 has been positioned upon evaporator 31.

It will be seen from the foregoing that I have provided an improved refrigerating apparatus in 10 that I have made provisions for modifying at will the refrigerating effect thereof produced within the food storage compartment of the refrigerator cabinet. My invention renders the refrigerating apparatus universal in use at a cost 15 which is negligible to the manufacturer of the apparatus. I have provided an improved double-refrigerant refrigerating system wherein the secondary volatile refrigerating system or circuit can be readily and quickly removed from the primary refrigerating system to meet various food 20 storage requirements as desired by users of the apparatus. My improvement is novel in that I have retained several desirable features of conventional refrigerating apparatus while at the 25 same time accomplishing the objects sought with the addition of a single low cost element.

While the form of embodiment of the invention as herein disclosed constitutes a preferred form, 30 it is to be understood that other forms might be adopted, all coming within the scope of the claims which follow.

What is claimed is as follows:

1. Refrigerating apparatus comprising in combination, a cabinet having a plurality of walls 35 forming a food storage compartment therein, an evaporator of a closed primary refrigerating system disposed in said food storage compartment, said evaporator being constructed and arranged to provide a freezing chamber within the food storage compartment, said closed primary refrigerating system including a refrigerant translating portion for circulating refrigerant to and from said evaporator to cause same to produce a refrigerating effect, means removably associated 40 with said evaporator and forming a secondary volatile refrigerant circuit, said means including a refrigerant condensing portion in direct thermal contact with a portion of said evaporator and a refrigerant evaporating portion spaced from other portions of said evaporator for cooling and causing circulation of air within said food storage compartment, insulating means closing the space 45 between said evaporator and said secondary volatile refrigerant circuit forming means for substantially isolating said evaporator from the circulating air, and said closing means being resilient to permit deformation thereof upon moving said secondary volatile refrigerant forming 50 means relative to said evaporator for removing same therefrom.

2. Refrigerating apparatus comprising in combination, a cabinet having a plurality of walls 55 forming a food storage compartment therein, an evaporator of a closed primary refrigerating system disposed in said food storage compartment, said evaporator being constructed and arranged to provide a freezing chamber within the food storage compartment, said closed primary refrigerating system including a refrigerant translating portion for circulating refrigerant to and from said evaporator to cause same to produce a refrigerating effect, means associated with said evaporator forming a secondary volatile refrigerant circuit and being removable horizontally 60

therefrom, said means including a refrigerant condensing portion in direct thermal contact with an upper portion of said evaporator and a refrigerant evaporating portion spaced from all other portions of said evaporator for cooling and causing circulation of air within said food storage compartment, a molded rubber element closing the space between said evaporator and said secondary volatile refrigerant circuit forming means for substantially isolating said evaporator from the circulating air, and said molded rubber element being flexible to permit deformation thereof upon moving said secondary volatile refrigerant circuit forming means horizontally relative to 65 said evaporator for removing same therefrom. 15

3. Refrigerating apparatus comprising in combination, a cabinet having a plurality of horizontal and upright walls forming a food storage compartment therein, one of said upright cabinet walls having an opening therein providing access 20 to said food storage compartment, a door for normally closing said compartment access opening, an evaporator of a closed primary refrigerating system located within said compartment and disposed in horizontal alignment with said compartment access opening, said evaporator comprising a plurality of refrigerant evaporating walls formed to provide an elongated box-like freezing chamber within said food storage compartment, said closed primary refrigerating system including a refrigerant translating portion 25 for circulating refrigerant to and from said evaporator to cause same to produce a refrigerating effect, a double walled box-like structure surrounding the refrigerant evaporating walls of 30 said evaporator to substantially isolate same from air within said compartment and forming a secondary volatile refrigerant circuit, said double walled structure including a refrigerant condensing portion in direct thermal contact with 35 upper walls of said evaporator and a refrigerant evaporating portion spaced from all other walls of said evaporator for cooling and causing circulation of air within said food storage compartment, and said structure being carried by said 40 evaporator and being movable horizontally relative thereto to remove same therefrom through 45 said compartment access opening. 50

4. Refrigerating apparatus comprising in combination, a cabinet having a plurality of walls forming a food storage compartment therein, an evaporator of a closed primary refrigerating system disposed in said food compartment, said evaporator being constructed and arranged to 55 provide a freezing chamber within said food storage compartment, said closed primary refrigerating system including a refrigerant translating portion for circulating refrigerant to and from said evaporator to cause same to produce a refrigerating effect, means extending around said evaporator having a refrigerant condensing portion in direct thermal contact therewith and a refrigerant evaporating portion spaced therefrom to form a secondary volatile refrigerant circuit 60 for cooling and causing circulation of air within said food storage compartment, said means being removable from said evaporator, means closing the space between said evaporator and said secondary volatile refrigerant circuit forming means for substantially isolating said evaporator from the circulating air, and said closing means being detachable to permit removal of said secondary volatile refrigerant circuit forming means from 65 the evaporator. 70

5. Refrigerating apparatus comprising in combination, a cabinet having a plurality of walls forming a food storage compartment therein, an evaporator of a closed primary refrigerating system disposed in said food compartment, said evaporator being constructed and arranged to provide a freezing chamber within said food storage compartment, said closed primary refrigerating system including a refrigerant transmitting portion for circulating refrigerant to and from said evaporator to cause same to produce a refrigerating effect, means extending around said evaporator having a refrigerant condensing portion in direct thermal contact therewith and a refrigerant evaporating portion spaced therefrom to form a secondary volatile refrigerant circuit for cooling and causing circulation of air within said food storage compartment, said means being removable from said evaporator, means engaging said evaporator and being secured to said secondary volatile refrigerant circuit forming means for closing the space therebetween to substantially isolate said evaporator from the circulating air, and said closing means being formed of resilient insulating material to permit deflection thereof upon moving said secondary refrigerant circuit forming means relative to said evaporator for removing same therefrom. 5
- 10
- 10 refrigerating effect, means extending around said evaporator having a refrigerant condensing portion in direct thermal contact therewith and a refrigerant evaporating portion spaced therefrom to form a secondary volatile refrigerant circuit for cooling and causing circulation of air within said food storage compartment, said means being removable from said evaporator, means engaging said evaporator and being secured to said secondary volatile refrigerant circuit forming means for closing the space therebetween to substantially isolate said evaporator from the circulating air, and said closing means being formed of resilient insulating material to permit deflection thereof upon moving said secondary refrigerant circuit forming means relative to said evaporator for removing same therefrom. 10
